WINDOW SASH ATTACHMENT

Alfred Cipressi, Philadelphia, Pa.

Application July 28, 1943, Serial No. 496,561

4 Claims. (Cl. 20—48)

This invention relates to attachments for windows of the upper and lower sliding sash type, and its general object is to provide an attachment that includes a metallic frame for each sash, the latter being hinged to its frame to allow horizontal swinging movement of the sash to facilitate washing the same, and the frames are slidably mounted in the main window frame to bring about raising and lowering of the sash in the usual manner.

A further object is to provide a window attachment that includes sliding sash frames having sashes hinged thereto, and means are carried by the sashes to not only provide a weatherproof joint between the sliding frames and the main frame, but certain of said means act as latches for securing the sashes in closed position against swinging movement on their hinges.

Another object is to provide a window attachment of the character set forth, that is simple in construction, inexpensive to manufacture, easy to install and extremely efficient in operation, use and service.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a perspective view illustrating the upper and lower sash units with the lower sash swung on its hinges to open position.

Figure 2 is a vertical sectional view taken through the sash units installed in the main window frame and in closed position.

Figure 3 is a sectional view taken approximately on line 3—3 of Figure 2, looking in the direction of the arrows.

Figure 4 is a perspective view of the sliding frame for the upper sash.

Figure 5 is a perspective view of the pivoted weather and latching strip for the upper sliding frame.

Figure 6 is a perspective view of the fixed weather strip for the upper sliding frame.

Figure 7 is a perspective view of the sliding frame for the lower sash.

Figure 8 is a perspective view of the fixed weather strip for the lower sliding frame.

Figure 9 is a perspective view of the pivoted

weather and latching strip for the lower sliding frame.

Referring to the drawings in detail, it will be noted that the main frame for the window is indicated by the letter A and includes inner and outer retaining beads B and C, parting beads D, and inner and outer guiding beads E and F, the latter cooperating with the retaining and parting beads for slidably mounting the sash units within the main frame, as will be apparent upon inspection of Figure 3.

The lower sash unit frame as best shown in Figure 7, is substantially U-shape, in that it includes a flat base member 1 and flat side members 2 and 3 formed on and rising from the ends of the member 1 for disposal in parallelism with each other. The members 2 and 3 each have a flange 4 formed on or otherwise fixed to the outer edge thereof throughout its height and in a manner, whereby the flange extends laterally upon opposite sides of its member, for the inner portions 5 of the flanges 4 to provide stops for the side rails of the lower sash G, while the outer portion 6 of one of the flanges 4 bears against the parting bead D on the hinged side of the lower sash, and the outer portion 6 of the other flange 4 bears against a flanged weather strip 6' that is set in and fixed to the main frame for disposal in engagement with the inner face of the bead D at the hinged side of the upper sash, as clearly shown in Figure 3. The latter bead D may be eliminated as the strip 6' can take the place thereof.

The lower sash G is hingedly associated with its frame, and for that purpose one side rail of the lower sash has hinge leaves 7 fixed thereto, the leaves including the usual barrels registering with like barrels 8 formed on the side member 2 for receiving hinge pins, as best shown in Figure 7.

Fixed to the side rail which has the leaves 7 secured thereto is a weather strip 9 of a length substantially coextensive with the height of that rail, the leaves 7 being countersunk within the rail with the strip 9 bearing against the same, and the strip is formed with a flange 10 along the length thereof to engage the adjacent inner retaining bead B which is provided with a flange, for that purpose, when the lower sash is swung on its hinges to closed position. The lower sash is held in closed position by a combined weather and latching strip 11, of a height substantially coextensive with the free side rail of the lower sash and the upper end of the strip 11 is reduced and pivotally connected to the upper end of the latter rail, as best shown in Figure 1. Secured

to the lower end of the strip 11 is a knob 12 for moving the same on its pivot, and the strip 11 is receivable between the opposed inner retaining bead B and the inner guiding bead E, as clearly shown in Figure 3. A knob 13 is secured to the lower end of the strip 9, to be used with the knob 12 to facilitate raising and lowering the lower unit, as will be apparent.

When the lower sash is in its closed position of Figure 3 it is engageable with the base member 1, and the top of the free side rail is engageable with an abutment member or tongue 14 that overlies the rail, as will be apparent upon inspection of Figure 1, which illustrates that the abutment member 14 is formed on the upper ends of the side member 3 and its flange 4, with the result it will be seen that the bearing relation of the sash with the base member and the abutment member will relieve strain on the hinges, when raising and lowering the sash.

The upper sash unit frame as best shown in Figure 4 is of inverted U-shape, in that it includes a flat upper member 15 and flat side members 16 and 17, the latter being formed on and depending from the ends of the upper member. A flange 18 is provided for each of the side members 16 and 17, the flanges being formed on the outer edges of the members 16 and 17 in a manner whereby they extend laterally upon opposite sides thereof, to provide inner portions 19 providing stops for the side rails of the upper sash H, as best shown in Figure 3, while the outer portions 20 are disposed between the outer retaining beads C and the outer guiding beads F for sliding movement, as will be apparent upon inspection of Figure 3.

The member 17 has hinge barrels 21 formed thereon, and these barrels register with barrels 22 of the hinge leaves 23 that are fixed to one side rail of the upper sash H, as shown in Figure 3. Hinge pins are of course mounted in the hinge barrels 21 and 23 for hingedly connecting the upper sash to the upper unit frame for swinging movement of the upper sash in a direction opposite to that of the swinging movement of the lower sash. Fixed to the side rail of the upper sash that has the leaves 23 secured thereto, is a weather strip 24 which bears against the leaves 23 to cover the same, thus rendering them invisible in the same manner as the leaves 7 of the lower sash G. The strip 24 is formed with a flange 25 along its length, and the flange is engageable with the flange of the weather strip 6 when the upper sash is in closed position, as shown in full lines in Figure 3.

A combined weather and latching strip 26 is likewise provided for the upper sash and has a reduced upper end pivotally connected to the upper end of the free side rail, as shown in Figure 1. The lower end of the strip 26 is formed with an apertured ear 27 extending laterally therefrom to provide a finger piece for moving the strip 26 into and out of operative position. When the strip 26 is in operative position, it is disposed between the parting bead D and the outer guiding bead F, that are arranged at the free side of the upper sash unit, as best shown in Figure 3, with the result it will be seen that the latter unit is guided in its sliding movement by the beads C, F and D, as well as the weather strip 6, and when the strip 26 is moved on its pivot from between the beads F and D, the upper sash is released to be swung to open position, as shown in dotted lines in Figure 3.

Secured to the outer faces of each of the side members 2, 3, 16 and 17, are strip blocks 28 having eyelets 29 secured to the upper ends thereof for the connection of sash cords K thereto, as best shown in Figure 1.

The frame for the upper sash is likewise provided with an abutment member or tongue 30 formed on the lower ends of the side member 16 and the inner portion 19 of the flange 18 that is formed on the member 16, the abutment member 30 having the upper sash resting thereon and the upper sash bears against the upper member 15, so that upon raising and lowering the upper sash, the strain is relieved from the hinges thereof.

From the above description and disclosure in the drawings, it will be obvious that my attachment not only carries the sashes for sliding movement, to bring about raising and lowering thereof in the usual manner, but the sashes are hingedly associated therewith for swinging movement in a horizontal plane, so that they can be disposed within a room, to bring about washing thereof or for replacing broken panes, in a safe and easy manner.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. In a window including a main frame and upper and lower sashes, a frame for each sash and fittingly engaging the same about three sides, side members included in each frame and having the sash thereof hingedly connected thereto for swinging movement in a horizontal plane, flanges formed on the outer edges of the side members along their length and extending laterally thereof to provide inner and outer portions, said inner portions being disposed in the path of the sashes to limit movement thereof within their frames when swung to closed position, a latching strip for each sash and associated with the main frame for holding the sash in closed position, each latching strip being pivoted at one end to the upper end of one side rail of its sash, strips secured to the opposite side rails of the sashes, and the latter strips together with the latching strips and said outer portions of the flanges being mounted for vertical sliding movement in the main frame for disposal of the sash frames in side by side relation.

2. In a window including a main frame and upper and lower sashes, a frame for each sash and fittingly engaging the same about three sides, side members included in each frame and having the sash thereof hingedly connected thereto for swinging movement in a horizontal plane, means bridging the lower ends of the side members of the frame of the lower sash and engaging the bottom rail of the sash, means bridging the upper ends of the side members of the frame of the upper sash and engaging the upper rail of the sash, means cooperating with the bridging means for engagement with the upper and lower rails of the sashes to relieve the strain from the hinges thereof when the sashes are in closed position, flanges formed on the outer edges of the side members along their length and extending laterally thereof to provide inner and outer portions, said inner portions being disposed in the path of the sashes to limit movement thereof within their

frames when swung to closed position, a latching strip for each sash and associated with the main frame for holding the sash in closed position, each latching strip being pivoted at one end to the upper end of one side rail of its sash, strips secured to the opposite side rails of the sashes, and the latter strips together with the latching strips and said outer portions of the flanges being mounted for vertical sliding movement in the main frame for disposal of the sash frames in side by side relation.

3. In a window including a main frame and upper and lower sashes, a substantially U-shaped frame for each sash and fittingly receiving the same about three sides, side members included in each frame and having the sash thereof hingedly connected thereto for swinging movement in a horizontal plane, flanges formed on the outer edges of the side members along their length and extending laterally thereof to provide inner and outer portions, said inner portions being disposed in the path of the sashes to limit movement thereof within their frames when swung to closed position, a latching strip for each sash and associated with the main frame for holding the sash in closed position, the latching strips being of a length substantially coextensive with the height of the side rails of the sashes and being pivotally connected to certain of said rails, strips secured to the other side rails and being of a length substantially coextensive with the height thereof, the latter strips together with the latching strips and said outer portions of the flanges being mounted for vertical sliding movement in the main frame for disposal

of the sash frames in side by side relation, knobs secured to the strips of the lower sash and providing handles, and a finger piece on the lower end of the latching strip of the upper sash.

- 5 4. A window including a main frame and upper and lower sashes, a substantially U-shaped frame for each sash and fittingly receiving the same about three sides, side members included in each frame and having the sash thereof hingedly connected thereto for swinging movement in a horizontal plane, flanges formed on the outer edges of the side members throughout their length and extending laterally thereof to provide inner and outer portions, said inner portions being disposed 10 in the path of the sashes to limit movement thereof within their frames when swung to closed position, a latching strip for each sash and associated with the main frame for holding the sash in closed position, the latching strips being pivotally connected to certain of the side rails of the sashes, strips secured to the other side rails of the sashes, the latter strips together with the latching strips and said outer portions of the flanges being mounted for vertical sliding movement in the 15 main frame for disposal of the sash frames in side by side relation, all of said strips and said outer portions cooperating with the main frame to provide weatherproof joints between the sash frames and the main frame, strip blocks secured to the outer faces of said side members, and eyelets secured to the strip blocks for connecting sash cords thereto.

ALFRED CIPRESSI.
